(57) **CLAIM**

I claim the ornamental design for a faucet, as shown and described.

DESCRIPTION

FIG. 1 is a perspective view of a faucet showing my new design;

FIG. 2 is another perspective view of the faucet as shown in FIG. 1;

FIG. 3 is front view of the faucet as shown in FIG. 1;

FIG. 4 is back view of the faucet as shown in FIG. 1;

FIG. 5 is left-side view of the faucet as shown in FIG. 1;

FIG. 6 is a right-side view of the faucet as shown in FIG. 1;

FIG. 7 is a top view of the faucet as shown in FIG. 1; and,

FIG. 8 is a bottom view of the faucet as shown in FIG. 1. No particular colour scheme forms part of the claimed design.
